UNITED STATES PATENT OFFICE.

EUNICE A. VAN WINKLE, OF WAVERLY, ILLINOIS.

COMBINATION GARMENT.

Application filed March 2, 1922. Serial No. 540,409.

To all whom it may concern:

Be it known that EUNICE A. VAN WINKLE, a citizen of the United States of America, residing at Waverly, in the county of Morgan and State of Illinois, has invented new and useful Improvements in Combination Garments, of which the following is a specification.

The object of the invention is to provide a combination garment adapted for performing the functions of a brassière, stays and hose supporters and embodying elements which operate mutually in performing their functions for the purpose of affording freedom of movement of the body and limbs to adapt it for use without restraining the wearer in connection with athletic and other exercises including dancing, walking, riding, etc., and also adapted to bear the strain of the hose supporters without imposing a perceptible downward pressure upon the shoulders,—the joint action of the several elements being disposed to encourage a correct posture and insuring a proper draping of the outer garments; and with these objects in view the invention consists in a construction and combination of parts of which a preferred embodiment is shown in the accompanying drawings, wherein:

Figure 1 is a view of the complete garment, shown applied.

Figure 2 is a rear view of the same.

Figure 3 is a side view showing the positions assumed by the elements when the wearer is in a stooping or sitting posture.

Figures 4 and 5 are respectively cross sectional and face views of the runner through which the equalizing cord plays.

The brassière 10 supported by shoulder straps 11 is provided with front and side darts 12 and 13, and preferably an under arm seam 14 is employed in connection with the side dart, and the stay or abdominal supporter in the general form of a band 15 and 45 preferably comprising the front upper and lower elements 15^a and 15^b is provided at the rear with an arched connecting element 16 springing from and carried by the side or under arm portions of the band as indicated at 17 in Figures 2 and 3 and detachably connected by snap buttons, hooks or other fasteners 18 at its crown to the center of the rear portion of the brassière, to establish a yielding connection between the brassière 55 and the supporter while permitting freedom of back bending movement of the wearer.

The supporter is provided at its sides or under arm portions with preferably elastic lacing 19 and the ends of the upper and lower elements of the front portion or section of the supporter are connected by closely spaced conventional fasteners of the hook or snap button type as indicated at 20.

The hose supporters depending from and directly associated with the band forming 65 the abdominal supporter consist of the side elements 21 and the front elements 22, of which the former embody a strap 23 provided with an adjusting member such as a buckle 24 with a looped portion 23^a extending through an eye 25, a looped tape 26 having terminal garments clasps 27 for engaging the hose, a rear attaching loop 28 terminally secured to the supporter and including elastic elements 29 to permit of a restrained yielding movement, and an equalizing connection 30 connecting the loop 28 with the eye 25 and passing through a runner 31 which is engaged with the loop 26, said runner being indicated in detail in Figures 4 and 5 and consisting of a blank of sheet metal or equivalent material folded upon itself to form a curved guide 31^a to permit of free sliding movement of the equalizing cord or connection therethrough; 75 the terminals of the blank being brought together and slotted as indicated at 31^b. The portions of the blank at the extremities of the guide 31^a are upturned to form harness 31^c bounding a portion constituting a saddle 90 31^d which forms a bearing or seat for the bight of the garment supporting loop 26. Thus the equalizing cord or connection 30 being connected by means of the straps 23 and 28 with the abdominal supporter is free to 95 slide through the runner to accommodate forward and rearward bending movements of the wearer, in order to equalize strains imposed upon the hose by reason of the knee bending movements, etc. At the same time 100 the strain applied from the hose through the loop 26 and the equalizing cord or connection 30 to the strap 23 a rear loop 28 serves to maintain the rear portion of the abdominal supporter in snug fitting relation 105 with the wearer to provide for a symmetrical appearance of the outer garment.

Connecting the intermediate portions of the brassière and band connecting arch with the brassière approximately in the plane of 110 underarm seams are elastic stays 32 which serve to maintain the proper relation of the

arched element with the brassière and maintain a proper downward strain upon the side portions of the latter to guard against displacement of the brassière particularly during movements involving the raising of the arms of the wearer, while affording a sufficient yielding quality to avoid strain on the garment or restraint to the movements.

10 The front members of the hose supporters are constructed substantially as are the side members thereof as above described with the exception that the strap 28^a which is connected by elastics 29^a with the supporter 15 consists of a single member instead of being 15 looped as shown at 28 and 29, and said front strap is connected with the member 15 at a shorter interval from the adjustable strap 23^a, so as to bring the line of strain of the front members of the hose supporters more 20 directly in front of the thighs while the tendency of the side members is to distribute the strain between the side and the back of the thighs to adapt the terminals thereof to sitting or forward bending postures of the 25 wearer.

Having described the invention, what is claimed as new and useful is:—

1. A combination garment having a brassière and an abdominal supporter carrying 30 hose supporting members, the hose supporter and brassière being connected by an arched member springing from the side or under arm portions of the supporter and attached at its center to the center of the 35 back of the brassière.

2. A combination garment having a brassière and an abdominal supporter carrying hose supporting members, the hose supporter and brassière being connected by an 40 arched member springing from the side or under arm portions of the supporter and attached at its center to the center of the back of the brassière, and the abdominal supporter being provided at its side or under arm portions with elastic lacing.

3. A combination garment having a shoulder supported brassière and an abdominal supporter carrying hose supporting members, connection between the side or under 50 arm portions of the abdominal supporter and the center of the back of the brassière being effected by rearwardly and upwardly convergent elements.

4. A combination garment having a brassière and an abdominal supporter carrying hose supporting members, the hose supporter and brassière being connected by an arched member springing from the side or under arm portions of the supporter and attached at its center to the center of the back of the brassière, detachably engaged with the brassière.

5. A combination garment having a brassière and an abdominal supporter carrying 65 hose supporting members, the hose sup-

porter and brassière being connected by an arched member springing from the side or under arm portions of the supporter and attached at its center to the center of the back of the brassière, detachably engaged with 70 the brassière, the supporter having side or under arm elastic lacing means.

6. A combination garment having a shoulder supported brassière and an abdominal supporter carrying hose supporting members, connection between the side or under arm portions of the abdominal supporter and the center of the back of the brassière being effected by rearwardly and upwardly convergent elements, the hose supporters 75 consisting of front and side members of which the latter are of looped form with their extremities in connection with the supporter respectively at its under arm and rear portions.

7. A combination garment having a shoulder supported brassière and an abdominal supporter carrying hose supporting members, connection between the side or under arm portions of the abdominal supporter and the center of the back of the brassière being effected by rearwardly and upwardly convergent elements, the hose supporters consisting of attaching elements secured to the supporter, a looped strap for terminal 90 attachment to the hose, and an equalizing connection between said attaching straps having a mutual running relation with the looped straps.

8. A combination garment having a shoulder supported brassière and an abdominal supporter carrying hose supporting members, connection between the side or under arm portions of the abdominal supporter and the center of the back of the brassière 105 being effected by rearwardly and upwardly convergent elements, the hose supporters consisting of attaching elements secured to the supporter, a looped strap for terminal attachment to the hose, and an equalizing connection between said attaching straps having a mutual running relation with the looped straps, one of said attaching straps 110 having elastic elements.

9. A combination garment having a shoulder supported brassière and an abdominal supporter carrying hose supporting members, connection between the side or under arm portions of the abdominal supporter and the center of the back of the brassière 115 being effected by rearwardly and upwardly convergent elements, the hose supporters consisting of attaching elements secured to the supporter, a looped strap for terminal attachment to the hose, and an equalizing connection between said attaching straps 120 having a mutual running relation with the looped straps, one of said attaching straps having elastic elements and the other being 125 provided with adjusting means.

10. A combination garment having a shoulder supported brassière and an abdominal supporter carrying hose supporting members, connection between the side or under 5 arm portions of the abdominal supporter and the center of the back of the brassière being effected by rearwardly and upwardly convergent elements, each hose supporting member having attaching straps connected by an equalizing cord, a looped hose engaging strap, and a runner having a guide for said equalizing cord and a transversely disposed saddle for running engagement of the hose engaging strap. 10
